MASSAGING MACHINE

Walter Wilburn Jones, El Paso, Tex.

Application June 30, 1937, Serial No. 151,220

1 Claim. (Cl. 128—56)

This invention is a machine for massaging the body, and an object of the invention is to provide a machine of this character particularly designed for massaging the back, and especially the spinal column, for inducing sleep and for invigorating and toning up the nerve system.

The invention, together with its objects and advantages, will be best understood from a study of the following description taken in connection with the accompanying drawings, wherein:

Figure 1 is a side elevational view of the machine.

Figure 2 is a sectional view through the massaging device per se.

Figure 3 is a bottom plan view of the massaging device; and

Figure 4 is a detail sectional view through a portion of the massaging device illustrating certain details hereinafter more fully referred to.

Referring to the drawings by reference numerals, it will be seen that the device includes a portable stand 5 consisting of a weighted base 6 mounted on rollers 7 and provided with brake screws 8 suitably mounted in the brackets provided for the rollers 7 and adjustable to engage the peripheries of the rollers to apply a braking action thereto, when desired.

Rising from the base 6 is a tubular standard 9 in which is slidably a rod 10 that is secured at the desired position of vertical adjustment through the medium of a screw 11.

At the upper end thereof the post or rod section 10 is provided with a lateral tubular arm 12 that at its free end is downturned and terminates in a socket 13.

Mounted on the free end of the arm 12 for universal movement relative thereto is a massaging device indicated generally by the reference numeral 14.

As clearly shown in Figures 2 and 3, the massaging device 14 comprises a hollow casing-like head 15 provided with a ball formation 16 that fits within the socket 13 to provide a universal connection between the head 15 and the arm 12.

The bottom of the casing 15 is closed through the medium of a block 17 of insulating material, and imbedded in the block 17 is a heating element in the form of a resistance coil 18 that is arranged in suitable circuit with a control switch 19 provided therefor and mounted on the rod 10.

Also, the plate 17 adjacent its opposite longitudinal edges, and its respective opposite end edges, is provided with openings that receive shanks 19 that extend therethrough and are pro-

vided at their inner ends with collars 20 that bear against the inner side of the plate 17. At their outer ends the shanks 19 are provided with disk-like heads 21 formed of rubber or other suitable material and equipped with integral 5 teeth or projections 22.

Housed within the casing 15 are springs 23 that at one end are convoluted about the inner ends of the shanks 19 and bear against the collars 20 for yieldably urging the teeth equipped 10 heads 21 into contact with the body being treated.

For revolving the head 15 there is mounted on the upper end of the post 10 an electric motor 24 and suitably connected with the armature shaft of the motor 24 is a flexible shaft 25 that has a 15 portion thereof extending through the arm 12 and the ball 16 to terminate within the casing or head 15. On the end of the flexible shaft 25 terminating within the casing or head 15 is a gear 26 that is in fixed engagement with an 20 internal ring gear 27 suitably provided internally of the head 15 and formed integrally with the top of the head, as shown in Figure 2.

It will thus be seen that drive is transmitted from the motor to the head 15 for revolving the latter, and in actual practice, while the head 15 is revolving, the massaging elements 21 are brought into contact with the body under treatment, whereby a thorough massaging of the body is effected.

Obviously, springs 23 act yieldably to cause the massage fingers or elements 21 to bear on the body being treated, thus insuring a contact of all the fingers with the body, the shanks 19 being independently movable so as to move inwardly 35 or outwardly with respect to the head 15 as the contour of the body may require.

For controlling the circuit to the motor 24, there is suitably mounted on the post 9 an electric switch 28.

Having thus described the invention, what is claimed as new is:

A massage device comprising a hollow supporting arm having a depending socketed end, a casing embodying spaced top and bottom walls, 45 a ball on the outer surface of the top wall swivelly and rotatably fitted in said socket, said ball having a bore extending therethrough into the casing, a drive shaft extending through the bore into the casing, a drive connection between the 50 shaft and the top wall of the casing for rotating the casing, and a plurality of spring-projected massage elements slidably carried by the bottom wall,

WALTER WILBURN JONES.
